SHIRT PROTECTOR

Stephen Lighter, Milwaukee, Wis.

Application April 23, 1942, Serial No. 440,191

10 Claims. (Cl. 229—87)

The present invention relates generally to improvements in the art of wrapping laundered shirts or the like, and relates more specifically to an improved assemblage for folding and for subsequently protecting shirts or similar garments after they have been freshly laundered.

An object of the invention is to provide an improved shirt protector which is simple in construction and efficient in use.

It has heretofore been proposed as shown in my prior Patent No. 2,243,350, granted May 27, 1941, to provide a protective wrapper or retainer for maintaining a laundered shirt in neatly folded condition and in proper shape, by utilizing a shirt embracing band adapted to surround the folded shirt and having thereon a panel extending upwardly from the center of the front section of the band, the panel being co-operative with the forward portion of the inner shirt collar to cause the panel to swing upwardly, and this panel being provided with opposite side tabs adapted to co-operate with the rear surfaces of both collar lapels to prevent crushing thereof. While this prior shirt protector is entirely satisfactory in operation and has gone into extensive commercial use, it requires some means such as an elongated plate hingedly connected to the upper extremity of the central panel and co-operative with the interior of the inner shirt collar, in order to hold the panel in upstanding position and the tabs against the inner or rear surfaces of the lapels. It is also rather difficult to remove an ordinary rectangular flat folding board from a shirt to which one of the prior protectors has been initially applied, because of the formation of the shirt embracing band with interlocking ends. Then too, it has been found that the use of the transverse collar engaging plate for holding the panel up, is not essential and that valuable stock can be saved by eliminating this reenforcing plate.

It is therefore a more specific object of my present invention to provide an improved shirt and collar protector of the above described general type, wherein the collar lapel tabs or supports are maintained in active position by causing the same to coact with the retainer or band which engages the shirt bosom, thereby making it unnecessary to provide an inner collar stiffening or re-enforcing plate.

Another specific object of this invention is to provide a new and useful shirt protective device, which can be readily constructed with minimum stock, and which may also be quickly and conveniently applied to folded shirts or the like.

A further specific object of the present inven-

tion is to provide an improved shirt folding and retaining assemblage which can be readily manipulated to neatly fold and to subsequently maintain shirts in shape and in folded condition, without utilizing separate fasteners of any kind.

Still another specific object of my invention is to provide an extremely simple and highly effective shirt and collar protector which is attractive in appearance, and which may be manufactured and sold at moderate cost.

These and other specific objects and advantages of the invention will be apparent from the following detailed description.

A clear conception of embodiments of the several features constituting the present improvement, and of the mode of constructing and of applying the invention to folded shirts, may be had by referring to the drawings accompanying and forming a part of this specification wherein like reference characters designate the same or similar parts in various views.

Fig. 1 is a plan view of a typical folded shirt with the folding board still disposed therein and having one type of my improved protector superimposed thereon preparatory to application of the protector;

Fig. 2 is a perspective view of the finally enwrapped and protected folded shirt of Fig. 1, with the folding board removed;

Fig. 3 is a fragmentary top view of the protector type shown in Figs. 1 and 2, showing how the central panel is maintained elevated by the opposite lapel supports;

Fig. 4 is a bottom or end view of the protector of Figs. 1 to 3 inclusive, showing the same assembled but removed from the shirt;

Fig. 5 is a plan view of a modified improved shirt and collar protector, having an inner shirt collar re-enforcing plate associated therewith;

Fig. 6 is a plan view of a folded shirt similar to that of Fig. 1, but with the modified protector of Fig. 5 initially superimposed thereon; and

Fig. 7 is a perspective view of a final shirt package enwrapped with the modified type of protector.

While the invention has been shown and described herein as having been incorporated in shirt wrapper and protective assemblages formed of cardboard stock and adapted to co-operate with folded shirts of a particular style, it is not my desire or intent to thereby unnecessarily restrict the scope or utility of the improvement.

Referring especially to Figs. 1 to 4 inclusive of the drawings, the improved shirt wrapper and protector disclosed therein is especially co-oper-

able with a shirt 9 which has been neatly folded about a flat folding board 10 and has a collar consisting of inner and outer portions 11, 12 respectively, the latter of which has front wings or lapels 13. The protector shown in Figs. 1 to 4 inclusive comprises in general a laterally elongated retainer 14 formed to extend transversely across the bosom 15 of the folded shirt 9 below the two part collar; a relatively narrow panel 16 projecting upwardly from the center of the upper front section 17 of the retainer 14; and a pair of supports 18 for the collar lapels 13, extending laterally away from the opposite sides of the panel 16, and each having its end 19 farthest from the panel 16 recessed for interlocking coaction with notched portions 20 formed on the retainer 14 so as to maintain the panel 16 in elevated condition relative to the plane of the shirt bosom 15.

While the flat shirt folding board 10 which may be formed of metal, cardboard, or other suitable stiff sheet material, is of generally rectangular shape, the opposite lower side portions of this board 10 are preferably provided with indentations or recesses 21 as shown in Figs. 1 and 6, for purposes to be later explained.

The improved protector is preferably formed of a single sheet of cardboard or the like with the grain running lengthwise of the retainer 14; and this retainer is also preferably formed as a band adapted to snugly embrace a folded shirt 9, and with its opposite end portions provided with interlockable notches or slits 22, 23. While only one fastening slit 22 is required, it is desirable to provide several complementary fastening slits 23 in order to accommodate folded shirts 9 of different widths; and the slits 22, 23 are so formed that the band retainer 14 during assemblage thereon, must first be pulled inwardly beyond its final folded position, and subsequently released and stretched outwardly, in order to insure proper interlocking of the coacting slits 22, 23. The opposite side recesses 21 of the folding board 10 will accommodate this initial inward pulling of the ends of the retainer band 14 during interlocking of these ends, and the band may thus be conveniently and quickly assembled without the aid of separate fasteners or adhesives.

The central panel 16 is preferably tapered as shown, and is hingedly connected to the retainer 14 along a score line 24 so as to permit the panel 16 to be readily elevated. The opposite side supports 18 may also be hingedly connected to the sides of the panel along score lines 25, but these score lines are not essential. These supports 18 may be cut directly from the stock of the transverse retainer 14, thereby leaving upwardly projecting parts 26 at the opposite sides of the front section of the retainer band, which serve to ultimately protect the shoulder portions of the folded shirt 9. The recessed ends 19 of the supports 18 are formed to interlock with the notched inwardly projecting resilient portions 20 of the retainer 14 so as to hold the panel 16 in elevated position and the supports 18 against the inner or rear surfaces of the collar lapels 13, when the protector is finally assembled upon the shirt 9.

When utilizing the invention as depicted in Figs. 1 to 4 inclusive, the shirt 9 should first be neatly and compactly folded about the flat board 10, after which the flat protector should be positioned across the shirt bosom 15 and with the parts 26 thereof beneath the tips of the collar lapels 13 as shown in Fig. 1. The narrowed

and slitted end portions of the retainer 14 will then be disposed in horizontal alinement with the side recesses 21 of the folding board 10, and these retainer end portions may then be folded along score lines 27 and interconnected at the rear of the folded shirt 9 to cause the band to snugly embrace the shirt assemblage. This operation is naturally facilitated by the recesses 21 at the opposite sides of the lower portion of the board 10; and when the retainer 14 has been thus caused to embrace the shirt 9, the band may be moved upwardly toward the collar beneath the lapels 13. This upward movement of the band retainer 14 may be accomplished by grasping the side supports 18 between two fingers to bend the same slightly inward, and by simultaneously pulling upwardly, and the panel 16 will then ride along the front part of the inner collar portion 11 and will be elevated at an oblique angle to the plane of the shirt bosom 15. As the panel 16 approaches its finally assembled position, the recessed ends 19 of the supports 18 will engage the notched adjacent portions 20 of the retainer 14 and will become interlocked therewith, and upon release of the supports 18 by the operator, these supports will snugly engage the inner faces of the lapels 13 and will maintain these lapels in proper position while at the same time holding the inner collar band 11 erect. The protector is shown assembled in Figs. 2, 3 and 4, and when properly applied will retain the shirt 9 and its collar in neatly wrapped condition, even after the folding board 10 is removed.

Referring specifically to Figs. 5 to 7 inclusive, the wrapping and protecting assemblage shown therein is the same in all respects to that illustrated in Figs. 1 to 4 inclusive, but the modified protector is additionally provided with a transverse upper retainer plate 28 which is hingedly connected to the upper extremity of the central panel 16 by means of a short transition section 29 having slits 30 at the opposite sides thereof. The plate 28 is preferably formed integral with the panel 16 and from the same piece of sheet stock from which the retainer 14, panel 16 and supports 18 are produced; and when the modified protector is initially applied to a folded shirt 9, the transverse plate should be disposed over the collar lapels 13 as shown in Fig. 6. When the band retainer 14 has been applied around the folded shirt 9 and is moved toward the collar, and the panel 16 and supports 18 have been assembled beneath the lapels 13, the transverse plate 28 may be folded at the transition section 29 into the inner collar portion 11, as in Fig. 7. The plate 28 will therefore additionally re-enforce the shirt collar assemblage, and will retain the same in proper shape even after removal of the folding board 10.

From the foregoing detailed description it will be apparent that my present invention provides an improved shirt protector which is simple in construction and highly efficient in use. The improved device is especially adapted to maintain the collar lapels of a folded shirt in proper position and to prevent crushing or wrinkling thereof, and the new protector can be readily constructed with minimum waste of stock and may also be quickly and conveniently applied to folded shirts without utilizing adhesives or separate fasteners of any kind. Both types of the improved protector illustrated and described herein will most effectively co-operate with the collar lapels of the shirts, and neither of these types will tend to crush the outer collar inward-

ly as has been done with prior shirt wrappers and protectors wherein wings were caused to extend outwardly over the top of the collar lapels. In each of the embodiments, the narrow panel 16 is firmly maintained on the order of an easel, in upstanding position, by the lateral supports 18 the extreme ends of which are so formed that they will dig into the soft shirt when engaged by the resilient notched portions 20 of the retainer 14. The tripod produced by the panel 16 co-operating with the opposite side supports 18, provides a rigid supporting assemblage for the shirt collar, and can be used either alone as in Figs. 1 to 4, or in conjunction with a panel 28 such as shown in Figs. 5 to 7, and the tripod can be quickly and conveniently assembled and interlocked with the retainer band notches 20 beneath the outer collar portion 12. The improved shirt wrapper has proven highly effective in actual use, is attractive in appearance, and may be manufactured and sold at moderate cost.

It should be understood that it is not desired to limit this invention to the exact details of construction or to the precise mode of use, herein shown and described, for various modifications within the scope of the appended claims may occur to persons skilled in the art.

I claim:

1. A shirt protector comprising, a retainer formed to extend transversely across the bosom of a folded shirt below the shirt collar and having laterally separated notched portions, a relatively narrow panel projecting upwardly from the center of the front section of said retainer, and a collar lapel support extending laterally from each side of said panel, each of said supports having its end farthest from said panel formed to coact with said notched retainer portions so as to maintain the panel in elevated condition relative to the plane of the shirt bosom when the protector is applied to a shirt.

2. A shirt protector as per claim 1, characterized thereby, that the panel is hingedly connected to the retainer, and that the ends of said collar supports are also notched for interlocking coaction with the retainer notches.

3. A shirt protector as per claim 1, characterized thereby, that the retainer is a band adapted to snugly embrace the shirt and having its opposite ends formed for inter-connection at the rear of the shirt.

4. A shirt protector as per claim 1, character-

ized thereby, that the shirt embracing retainer band with inter-connectible opposite ends and the panel and the lapel supports are formed of a single sheet of stock, and that the supports 5 are formed of stock derived from the body of the band.

5. A shirt protector as per claim 1, characterized thereby, that the protector has a flexible collar re-enforcing plate associated with the upper end of the panel and co-operable with the interior of the collar band.

6. A shirt protector as per claim 1, characterized thereby, that the flexible collar re-enforcing plate which is associated with the upper end of the panel is formed integral with the remainder of the protector, and has its medial portion hingedly connected with the upper panel end.

7. A shirt protector as per claim 1, characterized thereby, that a flat board which is insertable 20 within the shirt during folding thereof, is provided with opposite side recesses which are co-operable with the shirt embracing retainer band of the protector in order to facilitate inter-connection of the band ends.

8. A shirt protector as per claim 1, characterized thereby, that the inter-connectible ends of the shirt embracing retainer band are slotted to permit detachable slip connection of said ends and to accommodate shirt packages of different widths.

9. A shirt protector as per claim 1, characterized thereby, that the collar lapel supports are hingedly connected to the opposite sides of the panel, and that the opposite sides of the panel 35 are tapered upwardly toward each other.

10. A shirt protector comprising, a retainer formed to extend transversely across the bosom of a folded shirt and about the rear of the shirt below the collar and having laterally separated notched upper portions equi-distant from its central axis, a relatively narrow upwardly tapering panel formed integral with and projecting upwardly from said retainer midway between said notched portions, and a collar lapel support extending laterally from each side of said panel and being formed integral therewith, each of said supports having its end farthest from said panel notched for coaction with said notched retainer portions so as to maintain the panel in elevated condition relative to the plane of the shirt bosom when the protector is applied to a shirt.

STEPHEN LIGHTER.
